US0D1021238S

(12) **United States Design Patent** (10) Patent No.: **US D1,021,238 S**
(45) Date of Patent: ** Apr. 2, 2024

(54) HAIR CARE APPLIANCE

(71) Applicant: **SharkNinja Operating LLC**,
Needham, MA (US)

(72) Inventors: **Daniel Van Alphen**, Lexington, MA
(US); **Ramsey Lehman**, Brookline, MA
(US)

(73) Assignee: **SharkNinja Operating LLC**,
Needham, MA (US)

(**) Term: **15 Years**

(21) Appl. No.: **29/841,056**

(22) Filed: **Jun. 2, 2022**

(51) LOC (14) Cl. **28-03**

(52) U.S. Cl.

USPC **D28/18**

(57) CLAIM

The ornamental design for a hair care appliance, as shown and described.

DESCRIPTION

FIG. 1 is a front perspective view of one embodiment of a hair care appliance shown in a first, straight configuration; FIG. 2 is a front view of the hair care appliance of FIG. 1. FIG. 3 is a back view of the hair care appliance of FIG. 1; FIG. 4 is a left side view of the hair care appliance of FIG. 1;

FIG. 5 is a right side view of the hair care appliance of FIG. 1;

FIG. 6 is a top view of the hair care appliance of FIG. 1; and, FIG. 7 is a bottom view of the hair care appliance of FIG. 1.

The broken line shown in all of the drawing figures are for illustrative purposes only and form no part of the claimed design.

1 Claim, 4 Drawing Sheets
